UNITED STATES PATENT OFFICE.

HORACE W. BIKLE, OF PITTSBURGH, PENNSYLVANIA.

DESIGN FOR A BADGE, BUTTON, PIN, OR INSIGNIA.

49,325.

Specification for Design.

Patented July 11, 1916.

Application filed January 28, 1916. Serial No. 74,892. Term of patent 7 years.

To all whom it may concern:

Be it known that I, HORACE W. BIKLE, a citizen of the United States, residing at Pittsburgh, in the county of Allegheny and State of Pennsylvania, have invented a new, original, and ornamental Design for Badges, Buttons, Pins, or Insignia, of which the following is a specification, reference being had to the accompanying drawing, forming part thereof.

The figure is a plan view of a badge, but-

ton, pin, insignia, or similar article, showing my new design, the blank and shaded portions thereof indicating different colors.

I claim:

The ornamental design for a badge, button, pin, or insignia, as shown.

HORACE W. BIKLE.
